UNITED STATES PATENT OFFICE

ERVIN G. BAILEY, OF EASTON, PENNSYLVANIA, ASSIGNOR TO FULLER LEHIGH COMPANY, OF FULLERTON, PENNSYLVANIA, A CORPORATION OF DELAWARE

DISTRIBUTOR FOR GASES CARRYING SOLIDS IN SUSPENSION

Application filed July 27, 1929. Serial No. 381,667.

This invention relates to a device by means of which a stream of gases carrying solids in suspension can be divided into two or more branches in such a way that a uniform distribution of the gases and solids is obtained in the different branches. The invention is especially applicable for the purpose of dividing a stream of air carrying pulverized coal in suspension to be distributed to a plurality of burners for furnaces, but the invention is not restricted to this particular use.

Heretofore when attempts have been made to divide a stream of this character into two or more branches, difficulties have arisen because of the tendency for the divided streams to vary in the proportions of air to solids passing thereto, due to the fact that the solids sometimes form laminations in the main stream, some of which have larger percentages of solids to air than others. This objection is largely or entirely overcome by the present invention, and the several branches are provided with mixtures of gases and solids of like proportions.

The invention will be understood from the description in connection with the accompanying drawing in which Fig. 1 is a side view partly in section showing an illustrative embodiment of the invention; Fig. 2 is a plan view partly broken away; and Fig. 3 is a plan view showing a modification.

In the drawing reference character 1 indicates a vertically disposed pipe or conduit through which a stream of gases carrying solids in suspension is passed. An L or somewhat L-shaped connection is connected to the upper end of the pipe 1. The portion 2 of the L or L-shaped member connected to the pipe 1 is of tubular shape and merges into a hollow portion 3 extending at an angle, preferably at a right angle, to the portion 2 that is connected to the pipe 1. The portion 3 has upper and lower walls 3' and 3'' that expand outwardly somewhat fan-shaped, as more clearly seen in Fig. 2. These walls converge toward their wide ends so that the cross sectional area of the portion 3 is approximately the same from one end to the other. An angularly disposed wall 4, hav-

ing a flat surface at an angle of say 45° to the axis of the portion 2, is located in the connection between the portions 2 and 3 in such a position as to be struck by the incoming stream from the pipe 1. The upper end of the wall 4 is connected to the end of the upper wall 3' of the portion 3. A corresponding wall 4' may be provided parallel to the wall 4 on the opposite side therefrom and is connected to the lower wall 3'' of the portion 3.

The end of the portion 3 opposite the sloping wall 4 is divided into branches 5 that increase vertically and decrease horizontally in size toward the exit ends. Pipes 6 are connected to the branches 5. Each pipe 6 may, for example, lead to a burner 7 for a furnace when the stream is air carrying pulverized fuel. The tubes 8 represent water tubes that are located along the front wall of a furnace 70 which the burner 7 feeds. The housing or compartment 9 indicates an inlet for secondary air around the burner 7 for the furnace.

In the modification shown in Fig. 3 the portion 3 is indicated as having two branches 5 leading to the pipes 6 that may lead to burners. However, the operation is not changed materially by varying the number of branches 5 leading away from the portion 3.

In operation the stream of gases carrying solids is forced from the pipe 1 through the portion 2 and strikes against the flat surface of the inclined or sloping wall 4, causing the same to splatter and thoroughly mix or commingle the gases and solids uniformly as they pass into the portion 3, so that each branch 5 will receive a mixture with the same proportion of gas to solids as the other branches.

I claim:

1. In a device of the character described, a conduit for gases carrying solids in suspension, a flat surface against which said gases strike, a receptacle having an increasing dimension in one direction and a decreasing dimension in a direction at right angles to said first mentioned direction into which the gases

enter after striking said surface, and a plurality of outlets from said receptacle.

2. In a device of the character described, a conduit for gases carrying solids in suspension, a flat surface against which said gases strike, a fan shaped receptacle into which the gases enter after striking said surface, and a plurality of outlets from said receptacle.

3. In a device of the character described, a conduit for gases carrying solids in suspension, a flat surface located at an angle to the axis of said conduit against which said gases strike, a receptacle having an increasing dimension in one direction and a decreasing dimension in a direction at right angles to said first mentioned direction into which the gases enter after striking said surface, and a plurality of outlets from said receptacle.

4. In a device of the character described, a conduit for gases carrying solids in suspension, a flat surface against which said gases strike, a receptacle into which the gases enter after striking said surface, said receptacle having closely spaced converging upper and lower walls, and a plurality of outlets from said receptacle.

5. A distributor for gases carrying solids in suspension which comprises an **L** with upper and lower walls increasing in width toward one end, an inlet into the opposite end of said **L**, and a plurality of outlets from the first-named end of said **L**.

6. A distributor for gases carrying solids in suspension which comprises an **L** with upper and lower walls increasing in width toward one end, an inlet into the opposite end of said **L** toward the small end of said walls, and a plurality of outlets from the first-named end of said **L**.

7. A distributor for gases carrying solids in suspension which comprises an **L** with upper and lower walls increasing in width toward one end, an inlet into said **L** at the small end of said walls, and a plurality of outlets from the large end of said **L**.

ERVIN G. BAILEY.
